US00D998577S

(12) **United States Design Patent** (10) **Patent No.:** **US D998,577 S**
Tomori (45) **Date of Patent:** **** Sep. 12, 2023**

(54) **TEMPORARY PROTECTIVE FILM FOR MANUFACTURING SEMICONDUCTOR DEVICES**

(71) Applicant: **Showa Denko Materials Co., Ltd.**, Tokyo (JP)

(72) Inventor: **Naoki Tomori**, Tokyo (JP)

(73) Assignee: **RESONAC CORPORATION**, Tokyo (JP)

(**) Term: **15 Years**

(21) Appl. No.: **29/834,586**

(22) Filed: **Apr. 13, 2022**

Related U.S. Application Data

(62) Division of application No. 35/510,733, filed on May 7, 2020 (U.S. filing date under 35 U.S.C. 384), and having an international filing date of May 7, 2020, now Pat. No. Des. 962,882.

(57) **CLAIM**

The ornamental design for a temporary protective film for manufacturing semiconductor devices, as shown and described.

DESCRIPTION

FIG. 1 is a perspective view of a temporary protective film for manufacturing semiconductor devices of the present invention;

FIG. 2 is a front view of the thereof.

FIG. 3 is a rear view of the thereof.

FIG. 4 is a top view of the thereof.

FIG. 5 is a bottom view of the thereof.

FIG. 6 is a left side view of the thereof.

FIG. 7 is a right side view of the thereof; and,

FIG. 8 is a sectional view taken along the line 8-8 of FIG. 6.

1 Claim, 8 Drawing Sheets
